UNITED STATES PATENT OFFICE.

HANS DORN, OF SUHL, GERMANY.

AMMUNITION FOR SELECTIVE SHOOTING.

949,063.

Specification of Letters Patent. Patented Feb. 15, 1910.

Application filed August 3, 1909. Serial No. 511,027.

To all whom it may concern:

Be it known that I, HANS DORN, citizen of the German Empire, residing at No. 26 Heinrichserstrasse, Suhl, Germany, have invented certain new and useful Improvements in Ammunition for Selective Shooting, of which the following is a specification.

This invention relates to ammunition for selective sporting.

10 Cartridges to be discharged from shooting guns are known, in which the projectile consisting of a shot containing capsule can be discharged either after the manner of the ball shot, the small shot remaining compact during the trajectory of flight, or after the manner of an ordinary small or grapeshot according as the respective main charge or an alternative charge is caused to explode for the spreading effect.

20 This invention has for its object to prevent, as it is already known, always only one of two alternative powder charges being ignited, also to adapt the cartridge arrangement not merely for an alternative mode of 25 firing as a ball shot on the one hand or as a small shot on the other hand but to afford the marksman an opportunity to select from at least three modes of firing; the marksman must be able to use the same cartridge 1 for 30 a ball shot, 2 for a close grape-shot and 3 for a distant grape-shot, *i. e.* to predetermine the mode of firing by way of selection with regard to the effect of either 1, 2 or 3. The fourth possibility of selection is preferably the mode of firing with ordinary 35 small shot according to which the main charge and the extra charge—contained within the projectile chamber—are caused to explode simultaneously.

40 In carrying out the invention, special ignition retarding fuses are provided in connection with the projectile within the cartridge in a peculiar manner. The employment of the cartridge hereinafter described 45 in various modifications necessitates the adoption of a shooting gun, in which percussive means are provided, which not only control a single main priming point in the cartridge but also permit a plurality of igniting accessories to be operated by way of 50 selection. The special construction of such shot gun does not come within the scope of this invention but it may be stated for a better understanding of the invention that 55 the shot gun is preferably provided with several triggers, each of which individually

controls the selective firing of the cartridge, as hereinafter fully explained.

Referring to the accompanying drawings: Figure 1 represents the longitudinal section 60 of a main constructional form of the cartridge according to the invention; Fig. 2 is a cross-section according to line A—B and Fig. 3 is an end view of the cartridge according to Fig. 1; Fig. 4 represents a modification with respect to the arrangement of the igniting and fusing device in the bottom of the projectile of the cartridge; Fig. 5 is an end view of the bottom of the projectile with respect to Fig. 4; Fig. 6 represents a 70 further modification with respect to Figs. 1 and 4; Figs. 7 and 8 are longitudinal sections of the cartridge and end view of the bottom of the projectile for another modification with respect to the igniting or fusing 75 arrangement in the bottom of the projectile and the striking parts in the cartridge case, Figs. 9 and 10 represent sectional elevations of cartridges, where an annular ignition is provided for on the periphery and the ordinary central priming cap is provided on the bottom; Fig. 11 represents diagrammatically the horizontal section through the cartridge chamber together with percussion accessories of a shot gun, as may be adapted 80 for firing cartridges in the constructional form according to Figs. 9 and 10.

In Figs. 1-3, *a* is the cartridge case, which contains the main charge at *p*; this is ignited by the annular cap *i* on the bottom 90 part *b* of the case, channels *j* constituting the igniting paths through the bottom part *b*. The projectile body in Fig. 1, so far as it serves the purpose of the invention for a ball shot as well as for the small shot or the 95 grapeshot, preferably consists of a capsule *u* with releasable end cap *u'*, the front part of which is filled with shot *s*. Behind the filling of shot *s* is a tampion *v*; the space between the latter and the projectile bottom *w* traversed by three igniting or fusing channels *o o' o''* is filled at *q* with an extra 100 charge of powder. On this charge exploding after the projectile has left the barrel, the effect of the grapeshot will be produced 105 in the known manner, as owing to the releasable end cap *u'*, the capsule *u* does not burst and the charge of shot is ejected. In the event of the charge at *q* being ignited at practically the same time as the main charge 110 at *p*, the effect will be that of an ordinary small shot, the dispersion of small shot be-

ginning immediately in front of the muzzle. It is also obvious that if the main charge p alone is ignited, the projectile will be brought wholly (without an untimely separation of its parts) to the mark *i. e.* it will act as a ball shot. All three igniting or fusing channels $o o' o''$ are sealed at the side of the projectile bottom by diaphragm-like caps $r r' r''$ preferably consisting of thin metal (copper). They may be pierced by means of the plungers $c c' c''$ pointed at the front; these plungers are slidably mounted within the cartridge case a in a longitudinal direction and adapted to be advanced at the rearward end by pushers $x y z$. Percussive means which must be provided on the gun for firing the cartridge in addition to the usual percussive or striking means (for igniting the annular cap or primer i) serve for striking at will either the one or the other of the pushers $x y z$; the percussive means are not shown in the drawing but only represented by arrows. The pushers $x y z$ are arranged concentrically to one another, the rod-shaped pusher z in the middle forming the shank of the plunger c ; the sleeve-shaped piece y is connected to the plunger c' and the sleeve-shaped piece x to the plunger c'' , as shown in Fig. 1. In order that the pieces $x y z$, notwithstanding their sliding capacity, may have a tight fit at the bottom b of the case, lip-shaped projections are formed by annular grooves $x' y'$ around the inner edges of the pieces $x y z$, and the outer pusher x is surrounded by a packing sleeve b' which is either integral with the bottom b of the case, or is provided with a packing flange b'' as shown in Figs. 1 and 7. When the main charge explodes at p , the lips become closely pressed against each other, b' against x and b' against b'' so that the whole is locked, like a block, and the rearward escape of the powder gases is prevented. The traverse t is adapted to guide the plungers $c c' c''$. A tampion a' is also fitted for guiding the forward ends of the plungers in the muzzle of the case a . The plungers $c c' c''$ may be fluted so as to form igniting paths from p to the pierceable caps $r r' r''$. Of the three igniting channels $o o' o''$, one channel o communicates with the powder chamber q for a direct flashing ignition; the igniting channels o' and o'' are however provided with retardation fuses $f' f''$ of different burning lengths, so that f'' has a shorter burning period and f' a longer burning period up to the moment when the ignition is transmitted to the extra charge q .

The mode of employing a cartridge of such construction is as follows: The shooting gun for discharging or firing the cartridge is provided with the previously mentioned percussive means in order to strike singly or in succession the pushers $x y z$ and the annular primer i respectively. For the selective operation, it is assumed that the shooting gun is preferably provided with a plurality of triggers. One of these controls alone the annular percussion-flange or a simple plunger for striking against i ; when pulling this trigger, the main charge p alone will be ignited in the case a and the explosion of the main charge causes the projectile to fly out in its compact state, whereupon the shot takes place as a ball shot because the extra charge q remains uninfluenced. The mechanism in combination with the other (three) triggers is such that the single pusher $x y$ or z is driven forward by a percussive member, whereupon the primer striking action takes place at i . The plunger c or c' or c'' is thereby caused to pierce through the corresponding diaphragm cap $r r'$ or r'' . Fig. 1 shows how the cap r'' is pierced. The ignition taking place from p is transmitted in this case to the fuse f' before the projectile leaves the barrel; as the projectile has the trajectory of flight of a cylindrical projectile, the fuse f' burns through to the extra charge q after a certain period and the action or effect of the grape-shot takes place on the driving away of the detachable capsule u' . If instead of the fuse f' , the shorter fuse is also actuated at f'' in the same manner, a grapeshot takes place at a shorter distance in front of the muzzle. If however the cap r is pierced by the operation of the plunger c , the explosion takes place at p and q almost simultaneously, because the channel o permits the flashing ignition to take place without retardation. As previously explained, the ordinary small shot takes place in this case. The fourfold possibility is thus afforded *i. e.* to fire the described cartridge either as a ball shot or the ordinary small shot or the grape shot at a short distance or the grape shot at a remote distance. It is obvious that the selection of the shot can be varied by providing auxiliary fuses; the one or other mode of operation, such as that for the single ball shot, may also be dispensed with. For shooting or sporting purposes, it is however advisable to employ at least two modes of small or grape shot.

In Figs. 4 and 5, the modification of the projectile according to the arrangement of Fig. 1 is shown, wherein primer caps $h h' h''$ are provided instead of the diaphragm caps $r r' r''$. It is obvious that the striking of the plungers $c c' c''$ against such primer caps has practically the same effect as is described with respect to the arrangement according to Fig. 1, as a preliminary ignition of the respective different fuses takes place at $f' f''$ and the ignition of the main charge results therefrom. The corresponding parts of the projectile are moreover provided with the same reference letters as in Figs. 1-3.

136

A modified arrangement of the channels for transmitting the ignition is also shown in Fig. 6. In this example, only the one middle igniting channel σ^2 is provided with a longer fuse f^* . The empty channel reserved for direct flashing ignition is designated σ . The other empty channel σ' communicates with a transverse bore σ^x at an intermediate point of the fuse f^* so that when igniting therefrom, the burning period is shorter than when igniting in the channel σ^2 . The pierceable caps r', r^2 and r usually cover all these channels. If one or the other cap is opened by the medium of the plunger, the described varying effect takes place, as explained with reference to Fig. 1; when piercing the cap r^2 , the fuse f^* burns through its entire length and when piercing the cap r' , the fuse only burns through a portion of its length. Consequently, the initial ignition at r^2 applies to the grapeshot with effect at a remote distance and that at r' applies to the grapeshot with effect at a short distance.

Figs. 7 and 8 represent a simpler modification of the cartridge, in which the plungers $C C'$ are arranged as concentric parts. The tubular plunger C' controls with its points or tips an annular diaphragm d on the bottom of the projectile. When the diaphragm is pierced, a rearwardly situated annular fuse f is exposed and the initial ignition takes place from the main charge p . The ignition is transmitted with retardation to the extra charge q . If however the diaphragm cap r is perforated by the central plunger C the ignition of q takes place immediately in consequence of the ignition at p and an ordinary small shot results therefrom. The rearward parts of C and C' lead directly to a cylindrical socket b' of the case bottom b . A traverse T serves for guiding and limiting the stroke. For the purpose of producing a tight fit, lip-flanges are formed by concentric annular grooves at $e e$, and b' is a packing sleeve and b'' a packing flange which effect a hermetical locking of the parts $C C'$ on the explosion of the main charge p .

Figs. 9 and 10 represent two modifications of a cartridge, which is provided with annular priming instead of with bottom ignition. Fig. 11 shows diagrammatically, the corresponding construction of a fire arm, which is provided in the cartridge chamber with laterally striking percussive means.

The cartridge case a (according to Figs. 9 and 10) has only the ordinary central priming at i' , whereby the main charge p may be ignited, for instance, by means of striking bolt K (Fig. 11). The projectile part with shot s and extra charge q inclosed in the capsule u bears externally the embedded priming zones $m n$, which serve for the preliminary ignition of the fuse f'' and

f' respectively, according to Fig. 9. In Fig. 10, there is provided similarly as in Fig. 6, only one fuse f^* centrally; the ignition is started from m at the rear end or from n more to the front so that the retardation of ignition results therefrom at a longer or shorter interval.

Fig. 11 may be explained with respect to the employment of cartridges according to Figs. 9 and 10 as follows. Percussive pins 75 1, 2 are so arranged in combination with striking hammers $k k$ as percussive means for striking the annular priming zones $m n$ that they act laterally through holes in the barrel. Provided that the barrel is arranged as a recoil operated sliding barrel, an automatic cocking of the hammers $k k$ on both sides can be effected by means of the springs k' . The releasing members or stops are designated $g^1 g^2$. If, for example, the 85 release is effected at g^2 by the corresponding trigger, the hammer k with percussive pin 2 strikes downward and ignites the annular primer n , whereupon the striking bolt K advances and ignites the main charge of the 90 cartridge. Consequently, the projectile is discharged from the barrel after the respective fuse f or f^* has assumed its initial ignition from n . After a certain interval and at a certain distance, the explosion of 95 the charge of the projectile takes place with the effect of the grapeshot.

For preventing the bursting of the capsule u of the projectile, it may be split at the point or tip (as shown in Fig. 7) or perforated at the front part, or made thinner, or provided with a releasable end cap u' (Fig. 1), or the capsule u may be crimped over the end-cap u' (Fig. 4). By employing some twist, the centrifugal effect upon 100 the charge of shot will be checked in that the capsule u which contains the shot, is provided with riflings made with a reverse twist to the riflings of the gun barrel.

I claim:

1. In a cartridge of the character described, the combination with a case containing a main charge, of a projectile comprising a shot containing capsule having an extra charge therein, and a plurality of 115 means independent of each other and operative selectively whereby the capsule may be discharged either as a ball shot or as small shot.

2. In a cartridge of the character described, the combination with a case containing a main charge, of means for firing the same, a projectile comprising a shot containing capsule having an extra charge therein, and a plurality of means independent of 125 each other for selectively discharging the projectile as a ball shot, or as small shot at a predetermined time, of its trajectory.

3. In a cartridge of the character described, the combination with a case contain- 130

- ing a main charge adapted to be fired by suitable means, of a projectile comprising a shot containing capsule having an extra charge therein, ignition conducting means 5 interposed between the main charge and the extra charge, and means operative to place the extra charge in communication with the main charge whereby the extra charge may be fired through said ignition conducting 10 means from the main charge to discharge the capsule as a ball shot, or as small shot at a predetermined time.
4. In a cartridge of the character described, the combination with a case containing a main charge adapted to be fired, by suitable means, of a projectile comprising a shot containing capsule, an extra charge in the latter, there being a plurality of igniting paths leading to said extra charge, and 15 20 means for firing the extra charge from the main charge through a predetermined igniting path to drive off the capsule as a ball shot or small shot.
5. In a cartridge of the character described, the combination with a case containing a main charge adapted to be fired by suitable means, of a projectile adapted to be driven off either as a ball shot or as small shot by the main charge, and comprising a 25 30 shot containing capsule, an extra charge therein and a direct igniting path leading to said extra charge, a plurality of time fuses of different lengths leading to said extra charge, and selective percussive means 35 adapted to ignite the extra charge directly through the direct igniting path or indirectly through one of the fuses.
6. In a cartridge of the character described, the combination with a case containing a main charge adapted to be fired by suitable means, of a projectile adapted to be driven off either as a ball shot or as small shot by the main charge, and comprising a shot containing capsule, an extra charge 40 45 therein, there being a plurality of igniting paths leading to the extra charge, means for normally sealing communication between the main charge and the extra charge, and means for opening communication between the main charge and the extra charge through a desired igniting path.
7. In a cartridge of the character described, the combination with a case containing a main charge adapted to be fired by suitable means, of a projectile adapted to be driven off either as a ball shot or as small shot by the main charge and comprising a shot containing capsule, an extra charge 50 55 therein and a direct igniting path leading to said extra charge, a plurality of time fuses leading to said extra charge, means for normally sealing communication between the main charge and the extra charge, and means for opening communication between the main charge and the extra charge through a desired igniting path.
8. In a cartridge of the character described, the combination with a case containing a main charge adapted to be fired by suitable means, of a projectile adapted to be driven off either as a ball shot or as small shot by the main charge, and comprising a shot containing capsule, an extra charge 60 65 therein, there being a plurality of igniting paths leading from the main charge to the extra charge, means for normally sealing communication between the main charge and the extra charge, and a plurality of plungers adapted to be operated selectively to open communication between the main charge and the extra charge through a desired igniting path.
9. In a cartridge of the character described, the combination with a case containing a main charge adapted to be fired by suitable means, of a projectile adapted to be driven off either as a ball shot or as small shot by the main charge and comprising a shot containing capsule, an extra charge 70 75 80 85 90 95 95 therein, there being a plurality of igniting paths leading from the main charge to the extra charge, a plurality of plungers designed to open communication between the main charge and the extra charge, and means for locking said plungers together to prevent escape of gas upon firing the main charge.
10. In a cartridge of the character described, the combination with a case containing a main charge adapted to be fired by suitable means, of a projectile comprising a shot containing capsule, and extra charge therein, there being a plurality of igniting paths leading from the main charge to the extra charge, a cap in each igniting path to 100 105 110 close communication between the charges, and a plurality of pointed plungers designed to be operated selectively to pierce the caps and open communication between the main charge and the extra charge through a predetermined igniting path.
11. In a cartridge of the character described, the combination with a case containing a main charge, of a projectile comprising a shot containing capsule having an extra charge therein, a plurality of means independent of each other and operative selectively whereby the capsule may be discharged either as a ball shot or as small shot, and means for preventing the escape of gas 115 120 125 upon the firing of either charge.
